Primary Examiner — Anhdao Doan*Assistant Examiner* — Mary Shannon Malley(74) *Attorney, Agent, or Firm* — Antoinette G Giugliano; AGG Intellectual Property Law(57) **CLAIM**

The ornamental design for a case and cartridge gauge, as shown and described.

DESCRIPTION

FIG. 1 is a perspective view of the case and cartridge gauge, for use with a cartridge or case.

FIG. 2 is a rear elevation view thereof.

FIG. 3 is a front elevation view thereof.

FIG. 4 is a left side elevation view thereof.

FIG. 5 is a right side elevation view thereof.

FIG. 6 is a top view thereof.

FIG. 7 is a bottom view thereof.

FIG. 8 is a perspective view with a cartridge shown above, to be inserted; and,

FIG. 9 is a perspective view with a cartridge inserted into the case and cartridge gauge.

The broken lines show portions of the case and cartridge gauge that form no part of the claimed design.

1 Claim, 9 Drawing Sheets(56)
